UNITED STATES PATENT OFFICE.

JOSEPH ZOLOTAR, OF DETROIT, MICHIGAN.

DESIGN FOR A FONT OF TYPE.

Application filed September 29, 1924. Serial No. 10,925. Term of patent 14 years.

To all whom it may concern:

Be it known that I, JOSEPH ZOLOTAR, a citizen of Russia, residing at Detroit, in the county of Wayne and State of Michigan, have invented a new, original, and ornamental Design for a Font of Type, of which the following is a specification, reference being had to the accompanying drawing, forming part thereof.

The figure illustrates a font of type embodying my new design.

I claim:—

The ornamental design for a font of type, as shown.

JOSEPH ZOLOTAR.

Witnesses:

ANNA M. DORR,
S. LIGHTFOOT.
